W. M. FULLER.

Ore Amalgamator.

No. 81,767.

Patented Sept. 1, 1868.

WITNESSES:

L. L. Bond
C. A. West.

INVENTOR:

Willard M. Fuller

United States Patent Office.

WILLARD M. FULLER, OF CHICAGO, ILLINOIS.

Letters Patent No. 81,767, dated September 1, 1868; antedated August 28, 1868.

IMPROVED APPARATUS FOR AMALGAMATING GOLD AND SILVER.

The Schedule referred to in these Letters Patent and making part of the same.

TO ALL WHOM IT MAY CONCERN:

Be it known that I, WILLARD M. FULLER, of the city of Chicago, in the county of Cook, and State of Illinois, have invented certain new and useful Improvements in Amalgamators for Gold and Silver; and I do hereby declare that the following is a full, clear, and exact description thereof, reference being had to the accompanying drawings, making a part of this specification, in which—

Figure 1 represents a vertical section,

Figure 2 is an outside view, and

Figure 3 a top view.

Like letters refer to the same parts in all of the figures.

The nature and object of my invention consist in a new arrangement or device for drawing off the tailings, so as to insure an uninterrupted working of the apparatus or machine, in heating the amalgamating-agent enclosed within an outer shell or case, by the employment of a steam-jacket, and in so arranging the induction and eduction-pipes that the amalgamator can be used either as an air-vacuum amalgamator, by the use of an air-pump, or operated entirely by water, as may be desired or may be most convenient.

To enable others skilled in the art to make and use my invention, I will proceed to describe its construction and operation.

The outer case or shell B is made of cast iron or other suitable material, either in the form shown or in such other form as may be desired. If made of cast iron, it will be made in two or more parts, and secured together by suitable flanges and bolts, and made air-tight by iron filings "rusted" in, or by other suitable cement, or the parts may be "ground" together, as shown.

The upper portion is turned at the top and carried down near the bottom of the kettle C, so as to form a funnel-shaped inlet or induction-pipe A, or such inlet-pipe may be made separate and in any other suitable form, and be attached to the shell by any well-known means.

At the lower end of this inlet-pipe or chute A, I attach a deflector, H, which extends out from the pipe sufficiently far to distribute the comminuted quartz or gold-bearing substance through the amalgamating-agent, and to prevent such substance or material from passing by the side of or against such pipe. In this pipe I insert a shaft, F, which is supported in place by the arms or braces G, and is provided with a screw-thread where it passes through their connection, and at its lower end is provided with a valve or stop, I, by means of which the flow through the inlet is regulated, controlled, or stopped, as desired.

Inside of this case or shell I suspend or support, by suitable means, an amalgamating-kettle, C, which is so located that its bottom will be near the lower end of the inlet-pipe and its upper edge near the top of the shell, as shown. The amalgamating-agent is placed in this kettle, in a quantity sufficient to come above the deflector H. To the bottom and around this kettle is placed a steam-jacket, D, which is made to fit as far up the kettle as may be desired, and is also so located as to leave a space between it and the case B, and is supported in place by pendants, braces, or other suitable means.

Steam is admitted through the induction-pipe J, and passes out with the water of condensation through pipe K.

At the lower point or extremity of the case B, I attach the eduction or escape-pipe E, through which the tailings are discharged. This pipe or tube is made of considerable length, long enough to prevent a suction of water from the tank M in case an air-pump is applied to pipe L, and also to insure the descent of the prepared material through inlet A in case pipe L is closed and water only used.

The apparatus, as so far described, is more especially adapted to the use of mercury as the amalgamating-agent, and for this purpose it may be advisable to make the kettle of copper.

The application of steam is for the purpose of keeping the mercury at an elevated temperature, as in a heated condition it combines with the precious metals more readily and more rapidly, and its specific gravity in

proportion to its original bulk reduced somewhat, and to that extent is more easily operated or used in the apparatus.

When used with molten lead as an amalgamating-agent some changes of structure will be advisable.

It will be found best to make the kettle C a part of the shell or case, and connect the upper space with pipe E by three or four flues, for by this change it can be operated with less fuel than will be required when they (B and C) are entirely disconnected.

The size of the amalgamator will depend upon its use. From two to three feet in diameter will be sufficient. When complete, it is mounted in suitable masonry, and any well-known device can be used for feeding the prepared material.

In operation, the quartz or other material is comminuted in any of the machines in use for that purpose, and is fed into funnel or tube A, mixed with water, and passes from the tube into a bath of mercury, through which it rises, and passing over the upper edge of kettle C, passes down the annular space between the kettle and the shell, into the pipe E, from which it is discharged.

When used with water, it will be best to let the air out at L and fill it entire, and then it will continue to operate without pump or other aid so long as a supply of material is furnished.

When used with dry or heated material, water is placed in the tank M, so as to effectually close the pipe E against the admission of air, and an air-pump is applied to pipe L, so as to form a vacuum sufficient to force the material through the pipe A and the amalgamating-agent, as shown in Letters Patent heretofore granted to me on the 2d day of January and the 17th day of April, A. D. 1866.

In either case, when the material is wet or dry, or the machine operated by water or by exhausting the air, it will be found advantageous to have an interior kettle, and the tailings discharged over its sides and out at the bottom, for when particles are introduced, too heavy to be carried in water, or drawn off at one side by this arrangement, they will fall over the side of the kettle and out at the bottom, so that the machine will not clog, and will operate without interruption.

It is found to be difficult to pass sand or pulverized stone through a tube dry, as it will clog, but the water in the tube and tank will prevent it clogging in pipe E; but to insure its perfect working for dry material, a rod may be run up through the tank M into pipe E.

When operated with water, no tank will be required.

Having thus fully described my invention, what I claim as new, and desire to secure by Letters Patent, is—

1. Discharging the tailings of an amalgamator through a conduit or outlet, the mouth of which is immersed in liquid, so that it will close such conduit against the admission of air, and at the same time afford a free and uninterrupted passage for the tailings, substantially as specified.

2. The steam-jacket D, in combination with the kettle or vessel C and shell or case B, substantially as described.

3. The shell or case B, when provided with pipes E, L, and A, so that it can be operated interchangeably, either by water or by exhausting the air, substantially as specified.

4. Placing the kettle C within an air-tight case, B, so as to leave an annular space or flues between them, and connecting such space or flues with a discharge-pipe, E, placed below, substantially as specified.

WILLARD M. FULLER.
